UNITED STATES PATENT OFFICE.

CHARLES M. JOHNSON, OF NEW YORK, N. Y.

DELIVERY-SWITCH.

SPECIFICATION forming part of Letters Patent No. 681,057, dated August 20, 1901.

Application filed September 22, 1893. Serial No. 486,176. (No model.)

To all whom it may concern:

Be it known that I, CHARLES M. JOHNSON, a citizen of the United States, residing in the city, county, and State of New York, have invented a new and useful Improvement in Delivery-Switches for Pneumatic Tubes; and I do hereby declare that the following is a full, clear, and exact description of the invention, which will enable others skilled in the art to which it appertains to make and use the same.

In the drawings, Figure 1 represents a side view, partly in section, showing the delivery-switch in full lines when not in operative position and in dotted lines in position to switch the carrier from the main tube to the branch tube. Fig. 2 is a sectional view showing the carrier in position in the tube. Fig. 3 is a side view, partly in section, and showing in section certain parts not so shown in Fig. 1. Fig. 4 is an enlarged detail view of the circuit-closing mechanism at the operator's station.

My invention relates to a new and useful improvement in delivery-switches for pneumatic tubes in which by means of a circuit-closer at the cashier's desk the switch at the branch station at which it is desired to switch the carrier can be set in proper position, and it also relates to breaking the circuit by a carrier passing through the branch tube by which the delivery-switch is held in position to switch the carrier, whereby the delivery-switch is returned to its normal position.

It further relates to means for receiving, cushioning, and delivering carriers at each salesman's station.

My invention consists of certain novel features, arrangements, and combinations hereinafter described, and particularly pointed out in the claims.

40 A represents the main tube of a pneumatic system, to which the branch delivery-tube B is secured, as shown. Within the tube the carrier C is adapted to travel and has a wheel D in contact with a top rail or guide E in order to steady it therein during its passage through said system. Although I have shown this form of carrier, yet it will be understood that any other desired form may be used. At the end of the branch tube B there is arranged

45 50 a revolving air-cushion F for the carriers, consisting of a series of tubes. Three of these tubes G H J are shown, and they form air-

cushions for taking up the momentum of the carrier as it passes from the main tube into the branch tube and then into the receiving-tube in alinement with the branch tube, while the main air-current continues along through the main tube A. The branch tube B and receiving air-cushion F are supported by brackets K, resting upon the main tube A. The air-cushions G, H, and J are held together by means of frames L L', the frame L being fast on the shaft L² and the other end of the shaft loosely mounted in the bracket K. A ratchet L³ is mounted fast on said shaft, and with said ratchet a pawl L⁴ is adapted to engage and hold the revolving air-cushion F in fixed position when any of the tubes G H J are in alinement with the branch tube B. This pawl is pivoted in the bracket K at the point L⁵, and at its outer end an upright lever L⁶ is secured at one end and at the other end to the lever L⁷, pivoted to the branch tube B at L⁸. At the forward end of this lever L⁷ there is a projection L⁹, which is adapted to pass into the openings g' h' j' when the air-cushions G H J are respectively in alinement with the branch tube B. When the carrier passes along the branch tube B, having been switched into said branch tube in a manner hereinafter described, it strikes the projection L⁹, so as to lift said projection out of the opening g' in the air-cushion G, and this operation releases the pawl L⁴ from the ratchet L³, and the weight of the carrier in the air-cushion G revolves 85 said cushion from its position shown in the drawings and the air-cushion H is brought into alinement with the tube B, and the projection L⁹ drops into the opening h', and the pawl L⁴ engages with the ratchet L³ and holds 90 the revolving air-cushion F in proper position. As the air-cushion G passes from alinement with the tube B the carrier is discharged therefrom by gravity, due to the inclination of the tubes G, H, and J and by the rebound 95 caused by the compressed air in said tubes compressed ahead of the carrier. When the next carrier is received by the air-cushion H, this operation is repeated, and a like operation takes place with the other tubes when 100 the carriers are received therein.

The switch M extends across the junction of the main tube A with the branch tube B and is fixed on the shaft M', journaled at the

junction of the two tubes. Fixed on the same shaft is a lever M^2 , having at one end a weight M^3 , and at the other end extends downwardly a rod M^4 , with a soft-iron core 5 M^5 , moving in a helix M^6 . The main tube A and branch tube B are provided, respectively, with the offsets A' and B' for receiving the free end of the switch M, so as not to present an obstruction to the passage of the carrier either 10 through the main tube or the branch tube.

The normal position of the delivery-switch M is as shown in full lines, Fig. 1. Now when it is desired by the cashier to return a carrier to the salesman's station to which the 15 branch tube B leads, the switch O, which is normally held by a spring O' between the wire P' and the magnet P², is moved to close the circuit through the wires P P'. O² is a 20 clasp for holding the switch when moved to close the circuit. The closing of this circuit causes the helix M^6 to draw the soft-iron core M^5 downwardly and with it the lever M^2 , and thereby throws the switch-tongue M in the position as shown in dotted lines, Fig. 1. 25 The carrier is then inserted by the cashier and passes through the main tube A until it is deflected by the switch-tongue M into the branch tube B. The carrier, passing into the branch tube B, strikes the press-button Q, 30 which closes the circuit through the wires Q' Q². By the closing of this circuit the magnet P² is energized and draws the switch O off from the wires P P', and thereby breaks the circuit through these wires. The counterweight M^3 then returns the switch-tongue 35 M to its normal position, as shown in full lines. This breaking of the circuit by the carrier in the branch tube B signals to the cashier that the carrier has been delivered to 40 its proper station.

Although I have only shown one switch-station, yet it will be understood that as many switch-stations can be arranged as desired, involving the same principle of operation, as 45 described.

As will be understood by those skilled in the art the carriers are sent from the salesman to the cashier through a line of tube either above, alongside, or below the tube A, 50 and in which there is provided an opening closed by a suitable valve at each salesman's station, through which the carriers are introduced into the said tube leading to the cashier.

I do not limit myself to the exact arrangements and constructions shown, as the same 55 may be varied without departing from the spirit of my invention.

Having thus ascertained the nature and set forth the construction of my invention, what I claim as new, and desire to secure by Letters 60 Patent of the United States, is—

1. In a pneumatic-despatch-tube system, a main tube, a branch tube connected therewith, a switch normally closing said branch tube, a shaft on which said switch is mounted, a lever fast on said shaft, a weight on one end of said lever for holding the switch in position to close said branch tube, an electric circuit for operating said switch, a helix included in said circuit, an iron core for said 65 helix carried by the opposite end of said lever, a circuit-closer controlled by the operator for closing said circuit and thereby moving and retaining said switch in position to divert the carrier from the main tube into the 70 branch tube, and means operated by the diverted carrier for breaking said circuit and thereby releasing said switch which returns to its normal position to close said branch tube by the action of said weight. 80

2. In a pneumatic-despatch-tube system, an air-cushioning device located out of the line of travel of the main air-current for receiving and discharging the carriers consisting of two or more chambers suitably mounted and 85 adapted to be rotated, means for holding one of the chambers of said cushioning device normally in position to receive a carrier and adapted to be actuated by the said carrier to release the said chamber from its normal position, and means as the weight of the carrier 90 for revolving the said cushioning device to permit the discharge of the said carrier and to bring another chamber into position to receive the next carrier. 95

3. In a pneumatic-despatch-tube system, an air-cushioning device located out of the line of travel of the main air-current for receiving and discharging the carriers, means for holding said device normally in position to receive 100 a carrier and arranged to be actuated by the movement of said carrier entering said device to release said air-cushioning device from its normal position and thereby permit the discharge of the carrier. 105

In testimony whereof I have signed my name to this specification, in the presence of two subscribing witnesses, on this 18th day of September, 1893.

CHARLES M. JOHNSON.
